UNITED STATES PATENT OFFICE.

HARRY J. HICK, OF ALLIANCE, OHIO, ASSIGNOR TO THE McCASKEY REGISTER COMPANY, (INCORPORATED IN 1914,) OF ALLIANCE, OHIO, A CORPORATION OF OHIO.

LOCK.

1,232,034.

Specification of Letters Patent.

Patented July 3, 1917.

Application filed December 31, 1914. Serial No. 879,964.

To all whom it may concern:

Be it known that I, HARRY J. HICK, a citizen of the United States, residing at Alliance, in the county of Stark and State 5 of Ohio, have invented certain new and useful Improvements in Locks, of which the following is a specification.

The invention relates to locks for fire 10 proof cases or cabinets having all the locking parts placed within the case to protect the same from fire or other elements, and being arranged for locking without the use of a key while requiring a key to unlock them. Such a lock is set forth in my former 15 application, filed June 8, 1914, Serial No. 845,603.

The object of the present improvement is to construct and arrange the parts so that the locking elements located on the separable parts of the case or cabinet can be engaged for locking by a preliminary operation of the lock, while the cabinet parts are adjacent to but not in contact with each other; and so that by a further and final operation of the lock, the separable rims of the case or cabinet can be drawn, clamped and positively held in sealing contact with each other.

The general object of the invention, and 30 other attendant advantages, are attained by journaling or swiveling the locking plate on the periphery of a disk eccentrically secured crosswise on the inner end of the operating stem, by mounting the latch upon the eccentric disk and providing a keeper notch and 35 stops for the latch upon the periphery of the locking plate, and by providing stopping means for limiting the rotation of the locking plate in opposite directions.

40 The objects of the invention, thus briefly set forth, are attained by the preferred embodiment thereof illustrated in the accompanying drawings, forming part hereof, in which—

45 Figure 1 is an inner side elevation of the lock showing fragmentary parts of the case or cabinet clamped together and the locking elements in locked position;

Fig. 2, a section of the same on line 2—2, 50 Fig. 1;

Fig. 3, an elevation similar to Fig. 1, but showing the position of the locking elements at the end of the preliminary locking operation;

Fig. 4, a similar elevation showing the 55 normal unlocked position of the parts;

Fig. 5, a similar view showing an abnormal unlocked position of the parts;

Fig. 6, a detached perspective view of the 60 operating stem and the handles thereon;

Fig. 7, a detached perspective view of the eccentric disk;

Fig. 8, a detached perspective view of the 65 operating stem and handles with the eccentric disk secured on the inner end thereof;

Fig. 9, a detached perspective view of the 70 key cylinder; and

Fig. 10, a detached perspective view of the 75 key.

Similar numerals refer to similar parts 80 throughout the drawings.

The operating elements of the lock may include the stem 1, the handles 2, the key cylinder 3, the key 4, the eccentric disk 5; and the locking elements may include the 75 locking plate 6, the latch 7, and the locking post 8.

The stem 1 of the lock is provided with the journal 9 on its inner end extending into and through the corresponding bearing 10, 80 provided in the wall 11 of the case or cabinet; and when this wall is made of spaced surface plates 12, with intervening heat resisting material 13, as shown, the journal bearing 10 is preferably made in the bushing 14 secured between face plates 12 of the wall, which face plates are provided with apertures corresponding to the journal bearing in the bushing.

The annular shoulder 15 is preferably 90 provided on the stem of the lock in abutment with the outer face of the wall, and on the head 16 of the stem are secured the diametrical opposite radial handles 2 which can be conveniently grasped by the hand of 95 the operator for manipulating the lock and opening and closing the case.

The stem 1 is also provided with the axial bore 17, which extends from the inner end of the stem outward to a point within the 100 outer end thereof, thus leaving a solid front face 18 for the outer end or head of the stem; excepting that the slot 19 is provided therein for the entrance of the wings 20 of the key 4, which slot is preferably provided 105 with a central enlargement 21 for the shank 22 of the key.

The key cylinder 3 is fitted neatly in the

bore of the stem, and is provided in its outer end with the diametric slot 23 having the central enlargement 24 for receiving the wings 20 and the shank 22 of the key; and 5 on its inner end with the diametric tongue 25 protruding inward beyond the inner end of the stem.

The operating disk 5 is eccentrically secured on the inner end of the operating stem 10 as by means of the screw threaded shank 26 on the inner end of the stem entered in the corresponding aperture 27 in the disk and held thereon by the nut 26^a screwed upon the shank; the shank and the aperture being flattened on one side to stop a rotation 15 of the disk with reference to the stem.

The peripheral flange 28 extends outward from one side of the periphery of the disk, in which flange is provided the diametrically 20 opposite guide-ways 29 which receive and guide the latch 7 in its endwise movements, which latch is diametrically located on the inner side of the eccentric disk.

The latch 7 is slidably retained by the cap 25 screw 30, having its shank extended through the longitudinal slot 31 formed in the latch, and screwed into the body of the disk. The latch is also provided with the cam orifice 32 which receives the diametric tongue 25 30 on the inner end of the key cylinder; the edges of which tongue operate against the squared end 34 of the orifice for moving the latch in one direction, as shown in Fig. 4, and the flat sides of the tongue 35 may abut the same end of the orifice and may stop its movement in the opposite direction as shown in Figs. 1 and 2. The spring 35 is also provided in bearing engagement with the latch and the disk so 40 as to move the same in the opposite direction from its operation by the cylinder tongue, for the locking operation of the latch.

The locking plate 6 is rotatably mounted 45 or journaled on the eccentric disk so that it fits neatly around the entire periphery and has a portion 36 of its periphery circularly formed concentric with the center of the disk, over which peripheral portion of 50 the locking plate the lateral tongue 37 on one end of the latch extends when the same is in its unlocked position as shown in Figs. 3, 4 and 5; and while in this position the spring 35 acts to draw the tongue inward 55 until it is stopped by a sliding engagement with the periphery of the locking plate whenever the key cylinder is turned to bring the tongue 25 on its inner end transverse the latch, as shown in Figs. 3 and 5, which 60 is the position to which the cylinder must be turned to withdraw the key from the stem of the lock.

The stop 38 is provided at one end of the stop slide portion 36 of the locking plate, for 65 stopping the relative rotary movement of

the latch and the operating disk with reference to the locking plate in one direction; and the keeper notch 39 is provided in the periphery of the locking plate at the other end of the stop slide portion 36 thereof, 70 into which notch the tongue of the latch is adapted to enter and be held for holding and securing the operating and locking elements in locked position, as shown in Fig. 2; the entrance of the tongue into the notch 75 being effected by the action of the locking spring 35, whenever the tongue of the latch is rotated to register with the notch.

To prevent a binding of the latch tongue against the sides 40 and 40^a of the keeper 80 notch, the stop pin 41 is preferably provided on the side of the locking plate in the path of the lug 42 on the periphery of the eccentric disk; which lug is adapted to impinge and be stopped by the pin after the 85 latch tongue clears the one side 40 of the keeper notch and before it impinges the other side 40^a thereof, as shown in Fig. 1. It will be understood, however, that the use of the separate stop pin 41 is not essential, 90 for in lieu thereof, the side 40^a of the keeper notch may be extended, as shown, and will serve as a stop for the latch tongue, to prevent its moving beyond the keeper notch. 95

The stop post 43 is provided on the inner side of the wall 11 of the case or cabinet, for limiting the rotation of the locking plate in opposite directions. This post preferably protrudes into the slotted aperture 44 provided in the locking plate, one end 100 46 of which slot forms an abutment for limiting the rotation of the locking plate in one direction in its normal unlocked position, as shown in Fig. 4; and the other end 46^a forms an abutment for stopping the 105 rotation of the locking plate in the opposite direction in an abnormal unlocked position, as shown in Fig. 5.

And finally, the hook 47 is provided on the extended end 48 of the locking plate, 110 preferably diametrically opposite from the keeper notch 39 in the periphery thereof, which hook is adapted to engage and cooperate with the locking post 8 secured on the inner side of the wall 11^a, to the rim 115 of which wall the rim of the wall 11 is designed to be clamped and locked.

The locked relation of the parts is shown in Figs. 1 and 2, with the lateral tongue 37 of the latch engaged in the keeper notch 39 120 in the periphery of the locking plate. In this relation of the parts, it is evident that by inserting the wings of the key through the slot 18 in the stem into the slot 23 in the key cylinder, the cylinder can be rotated by the key so that the tongue 25 on its inner end will move the latch longitudinally, against the action of the locking spring, to disengage the lateral tongue 37 of the latch from the keeper notch 38 125 130

in the periphery of the locking plate. After the latch tongue is thus disengaged, the eccentric disk may be rotated by the stem and the handles, and the tongue of the latch 5 will pass over and along the stop slide portion 36 of the locking plate, as shown in Fig. 4.

The hook 47 being engaged with the locking post 8, the first portion of this rotation 10 swings the upper end of the locking plate to the right, as the lock is illustrated, by the rotation of the eccentric disk in the locking plate; and the turning of the eccentric disk in the locking plate carries the lateral 15 tongue of the latch from above the keeper notch, over and along the stop slide portion 36 of the locking plate, and also moves the locking plate downward until the end of the hook 47 is disengaged from the locking post, as shown, approximately, in Fig. 3.

If the key is permitted to remain in the lock with the tongue 25 on the key cylinder holding the latch tongue free of the stop 25 slide, during the further rotation of the eccentric disk, and after the hook 47 is disengaged from the locking post, the locking plate may hang without rotation on the eccentric disk, until the latch tongue strikes 30 the stop 38 on the locking plate, as shown, approximately, in Fig. 3; after which this plate is rotated with the eccentric disk to carry the hook 47 clear beyond the side of the locking post 8, and the turning may 35 continue until further rotation is stopped by contact of the end 46 of the aperture 44 with the stop post 43 on the wall of the case, as shown in Fig. 4.

When, however, the key is turned for removing from the stem, which turning rotates the cylinder tongue crosswise and permits the latch tongue to press against the stop slide by action of the locking spring; or when the swivel bearing of the locking plate 40 upon the eccentric disk is fitted closely enough to frictionally engage these parts; the locking plate may begin to rotate with the eccentric disk, just as soon as the hook thereon is disengaged from the locking post, 45 and may continue rotating until the plate is stopped by the post 43; after which the latch tongue will slide upon the stop slide and the eccentric disk will slide within the swivel bearing of the locking plate, until the latch 50 tongue impinges the stop 38 on the locking plate, as shown in Fig. 4, which prevents further movement of the locking elements. In this relation of the parts, which is referred to herein as the normal unlocked position of the lock, the handles of the stem are 55 preferably located in horizontal position so that they can be readily grasped for raising and lowering the upper portion of the case or cabinet on which they are mounted.

60 For reengaging the hook of the locking

plate with the locking post, and drawing, clamping and locking the separable parts of the case or cabinet together; the stem of the lock is first rotated by its handles in the reverse direction, until the shank 49 of the hook 65 impinges the side of the locking post 8, with the hook immediately below the post, as shown in Fig. 3; and as shown, this operation may be made when the rims of the case or cabinet parts are spaced apart at a 70 substantial interval from each other.

In event the key has been rotated to remove it from the stem, so that the cylinder tongue has been turned crosswise and the latch tongue is drawn against the stop slide 75 by action of the locking spring, as shown in Fig. 3; it is evident that the locking plate will be rotated more or less positively into this position by the turning of the eccentric disk, and the frictional engagement of the 80 latch tongue with the stop slide; and even though the key is not turned for removal from the stem, and the latch tongue is held free from the stop slide as shown in Fig. 4, the frictional engagement in the swivel bearing 85 on the locking plate on the eccentric disk, or the mere weight of the hooked end of the locking plate, serves to carry the hook laterally from the position shown in Fig. 4 to the position shown in Fig. 3, when the eccentric disk and latch are rotated to the position 90 shown in the latter figure.

When the parts of the lock are in this position, it is evident that a further rotation of the eccentric disk in the same direction will 100 cause the latch tongue to slide upon or move freely along the stop slide 36, depending upon the position of the key cylinder; and the turning of the eccentric disk in the swivel bearing of the locking plate, carries 105 the same upward so that its hook will first engage and then draw the locking post to clamp the rims of the separable parts of the case or cabinet together. The parts are so arranged that when this is accomplished, the 110 tongue of the latch will have moved directly above the keeper notch, into which the tongue is drawn by action of the locking spring, as shown in Fig. 2; the stop pin 41 on the locking plate and the stop shoulder 42 115 on the eccentric disk being arranged to stop the parts in proper position so that the latch tongue will freely enter the keeper notch without rubbing against either side thereof.

To prevent such a turning of the parts in 120 the reverse direction as will permit a locking of the latch tongue in the keeper notch, when the hook is disengaged from the locking post, as when the case or cabinet is opened as shown in Fig. 5; the contact of the end 125 46^a of the slot 45 against the pin 43 serves to stop the rotation of the eccentric disk and the locking plate in the reverse direction, before the latch tongue is rotated far enough to enter the keeper notch; the stopping of 130

the disk and latch being accomplished by the relative positions of the center of the eccentric disk and swivel bearing with reference to the center of the locking stem, which 5 prevents a further turning of the disk in its swivel bearing after the locking plate is stopped to prevent a further downward and lateral movement of the center of the eccentric disk toward the stop pin 43.

10 I claim:

1. A lock including a rotatable stem, an eccentric disk secured crosswise on the stem, a locking plate journaled around the periphery of the disk for rotation into and out 15 of locked position, and a latch on the disk movable crosswise thereof into and out of locking engagement with the plate.

2. A lock including a rotatable stem, an eccentric disk secured crosswise on the stem, 20 a latch on the disk movable crosswise thereof, and a locking plate journaled around the periphery of the disk having a notch in its periphery for locking the latch.

3. A lock including a rotatable stem, an eccentric disk secured crosswise on the stem, 25 a latch on the eccentric disk movable crosswise thereof, a locking plate journaled around the periphery of the disk having a notch in its periphery for locking the latch, and a locking spring for the latch.

4. A lock including a rotatable stem, an eccentric disk secured crosswise on the stem, a latch movable on the eccentric disk, a locking plate journaled on the periphery of the 35 disk having a notch for locking the latch, and a slide guide for holding the latch unlocked, a locking spring for the latch, and means for operating the latch.

5. A lock including a rotatable stem, an eccentric disk secured crosswise on the stem, 40 a latch on the disk movable crosswise thereof, a locking plate journaled around the periphery of the disk having a notch in its periphery for locking the latch, and means for unlocking the latch and holding it unlocked.

6. A lock including a rotatable stem, a locking plate eccentrically journaled crosswise around the stem, a latch on the inner end of the stem movable crosswise thereof, 50 and spring means for locking the latch to the plate.

7. A lock including a rotatable stem, a locking plate eccentrically journaled crosswise around the stem, a latch on the inner end of the stem movable crosswise thereof, 55 spring means for locking the latch to the plate, and means for unlocking the latch.

8. A lock including a rotatable stem, a locking plate eccentrically journaled crosswise around the stem, a latch on the inner end of the stem movable crosswise thereof, 60 spring means for locking the latch to the plate, and means extending through the lock plate, and means for unlocking the latch and holding it un- 65 locked.

9. A lock including a rotatable stem, a locking plate eccentrically journaled crosswise on the stem, a latch on the stem, spring means for locking the latch to the plate, means for unlocking the latch, and a slide 70 guide on the plate for holding the latch unlocked.

10. A lock including a rotatable stem, a locking plate eccentrically journaled crosswise on the stem having a locking notch and 75 a slide guide therein, a spring latch on the stem having a lateral tongue for bearing on the slide guide and engaging in the notch, and means for operating the latch.

11. A lock including a rotatable stem, a locking plate eccentrically journaled crosswise on the stem having a slide guide thereon with an abutment at one end and a locking notch at the other end, a spring latch on the stem having a lateral tongue for bearing 85 on the slide guide and engaging in the notch, and means for operating the latch.

12. A lock including a rotatable stem, a locking plate eccentrically journaled crosswise on the stem having a slide guide thereon with an abutment at one end and a locking notch at the other end with one side of the notch extended to form an abutment, a spring latch on the stem having a lateral tongue for bearing on the slide guide and 95 engaging in the notch, and means for operating the latch.

13. A lock including a rotatable stem, a locking plate eccentrically swiveled crosswise on the stem having a slide guide thereon with an abutment at one end and a locking notch at the other end, a spring latch on the stem having a tongue for bearing on the slide guide and engaging in the notch, and means for stopping the latch with its 105 tongue free from the sides of the notch.

14. A lock including a rotatable stem, a locking plate eccentrically journaled crosswise on the stem having a slide guide thereon with an abutment at one end and a locking notch at the other end, a spring latch on the stem having a lateral tongue for bearing on the slide guide and engaging in the notch, and means for stopping the locking 110 plate in normal unlocked position.

15. A lock including a rotatable stem, a locking plate eccentrically swiveled crosswise on the stem having a slide guide thereon with a locking notch at one end of the slide guide, a spring latch on the stem having a tongue for bearing on the slide guide and engaging in the notch when rotated in one direction, and means for stopping the locking plate when reversely rotated to prevent the latch tongue from entering the 120 locking notch.

16. A lock for separable parts of a case or cabinet, including a post on one part, a rotatable stem on the other part, a locking plate eccentrically swiveled on the stem hav- 130

- ing a shank with a hook thereon adapted to engage the post, and also having a slide guide thereon with an abutment at one end and a locking notch at the other end thereof, 5 disengaging the hook and swinging it free from the post, with means for stopping the plate in normal unlocked position. 30
- 5 a spring latch on the stem having a tongue for bearing on the slide guide and engaging in the notch, and means for operating the latch, whereby the stem can be rotated in one direction for engaging the hook with the 10 post and clamping the parts together, and in the opposite direction for disengaging the hook and swinging it free from the post.
17. A lock for separable parts of a case or cabinet, including a post on one part, a 15 rotatable stem on the other part, and a locking plate eccentrically swiveled on the stem having a shank with a hook thereon adapted to engage the post, and also having a slide guide thereon with an abutment at one 20 end and a locking notch at the other end thereof, a spring latch on the stem having a tongue for bearing on the stop slide and engaging 40 in the notch, and means for operating the latch, whereby the stem can be rotated in one direction for engaging the hook with the post and clamping the parts together, and in the opposite direction for disengag- 45 ing the hook and swinging it free from the post, with means for stopping the plate when rerotated in locking direction free of the post to prevent the latch tongue from entering the locking notch. 45
